UNITED STATES PATENT OFFICE.

HERMANN A. BRASSERT AND HOWARD H. JONES, OF CHICAGO, ILLINOIS.

HOT-BLAST STOVE.

1,238,097.

Specification of Letters Patent. Patented Aug. 28, 1917.

Application filed November 13, 1915. Serial No. 61,271.

To all whom it may concern:

Be it known that we, HERMANN A. BRASSERT and HOWARD H. JONES, both citizens of the United States, residing in Chicago, in the county of Cook and State of Illinois, have invented certain new and useful Improvements in Hot-Blast Stoves, of which the following is a specification.

Our invention relates to improvements in hot blast stoves, and particularly to a method of and apparatus for heating the blast for use in blast furnaces.

Hot blast stoves consist of a cylindrical steel shell filled with checker brick. The usual mode of operation is to heat these stoves by burning blast furnace gas in them for a period of time until the brick work is heated to the desired degree and sufficient heat has been stored in the checkers. Then the gas is shut off and air from the blowing engines is admitted at the opposite end of the stove, flowing through in the opposite direction to the previous flow of the gas. Thus the heat stored in the stove is transmitted from the brick work to the air, heating same to the desired temperature. Inasmuch as a large proportion of the total amount of blast furnace gas produced by the furnace is used in thus heating the blast, and inasmuch as the blast furnace gas has a commercial value equal to its equivalent in coal, it is very important that heating of the blast in the hot blast stoves be done as economically as possible.

In late years the washing of blast furnace gas is coming into more general use. With clean gas it is possible to employ much smaller checker openings in the stoves without danger of their clogging up, and the heating surface of a stove of given size is very much increased. It is evident that the larger the heating surface the more complete will be the transmission of heat from the gases to the brick work and back again from the brick work to the blast. By the use of washed gas the heating surface of stoves may be doubled and trebled by decreasing the size of checker openings and greatly increasing their number. However, in order to derive the benefit of this

improved construction it is necessary that the flow of the gas, as well as of the air, be equalized and that both be evenly distributed among the large number of checker openings and the entire area of the checker passes of the stove.

Our invention relates to the method as well as the construction of the apparatus, providing means for compelling an even distribution. It is a well known principle that a current or flow of liquid can be equalized and more evenly spread over a given area by putting a dam or weir across its passage, raising the head of water and compelling it to flow evenly over the entire face of the weir. Or baffles or screens placed in gas conduits have the same effect of spreading and equalizing the flow of gases. We have adopted this principle in hot blast stoves in the following manner.

Heretofore the checker openings were of the same size from end to end of each pass in a stove. If they were 9 inches at the bottom they were 9 inches at the top; if they were $4\frac{1}{2}$ inches at the bottom they were $4\frac{1}{2}$ inches at the top. We put one or more rows of smaller openings at the bottom of a pass, forming a restricted cross sectional area for the passage of the gases. After the air has entered the bottom of the stove and has filled the space under the arches supporting the checkers, it is confronted by this restriction and a slight back pressure is thereby created, compelling the air to divide equally among the many small openings before entering the larger ones above. In the same manner the flow of the descending gases is restricted and equalized. The provision of the smaller openings at the bottom of the checkers results in a further advantage. In order to construct a checker-work having the small openings most advantageously, it is desirable to use small bricks. These small bricks, however, cannot well be adapted as a support between the checkers and the arches. I am, therefore, able to use larger bricks to properly support the checkers. These larger bricks necessarily restrict the size of the opening into the checkers.

The invention will be more readily understood by reference to the accompanying drawings, wherein—

Figure 1 is a vertical section through a hot blast stove constructed in accordance with our invention;

Fig. 2 is a similar vertical section of the lower end of the stove, the view being taken at right angles to that of Fig. 1;

Fig. 3 is a sectional view on the line 3—3 of Fig. 1, and

Figs. 4 and 5 are sectional views on the lines 4—4 and 5—5 respectively of Fig. 1.

In the drawings the steel shell is indicated by the numeral 10, and the dome as 11. A gas burner 12 is provided in the lower end of the stove; the opening 13 indicates the connection to the chimney valve. The cold blast inlet is indicated at 14, and the hot blast outlet at 15. A vertical combustion chamber 16 is provided, which terminates in the dome, the heating chamber 16' within the shell being filled with standard checkers 17. In the present instance we provide, at the lower end of the checkers, two rows 18 of brick of larger size, which are directly supported by the arches 19. These larger bricks provide for restricted flue openings 20.

The gas is burned in the combustion chamber 16, the highly heated products of combustion reaching the dome and being reversed in their direction of travel, passing downward through the checkers until they reach the restricted openings 20 in the two bottom rows of checkers. The area of the flues at this point is reduced approximately one third as compared with the area of the flues in the standard checkers. The gases then enter the space below the arches, whence they escape through the chimney valve at 13. When the stove is reversed the cold blast enters through the opening 14 near the point where the gases are drawn off and, to a certain extent, backs up in the space below the arches. This for the reason that the flow through the smaller opening 20 is restricted, thereby causing the air to be evenly distributed and to pass through all of the checkers. As the air ascends through the checkers it gradually takes up the heat stored therein and flows downward through the combustion chamber, leaving the stove through the hot blast outlet at 15. In the case of the gases, these having passed through the combustion chamber and reversed their direction at the top under the dome, the natural tendency is to flow toward the center checkers or those forming the nearest path to the point where the chimney valve is located. Our construction, however, prevents this as the restriction in the bottom rows of the small checker openings is a far greater factor in the distribution of the gases than the effect of the location of

the chimney valve, or the effect of the gases tending to follow the hottest part of the stove near the center. It will be seen that we have counteracted all such influences in a very simple and effective manner, and have thereby greatly increased the efficiency of the stove.

While we have shown the invention as applied to a two pass stove, it will be understood that it may be applied with equal facility to three or four pass stoves, the same advantages accruing from the use thereof.

Our construction also has the advantage of greatly strengthening the support of the checker work. With modern stoves, which are in many cases 100 feet and more in height, great weight has to be supported at the bottom. With a decrease in the openings of the checkers the walls of the checkers have been made thinner and at the present time 2 $\frac{1}{2}$ " and 2" walls are used, or of even less thickness. It is impossible to get the necessary strength in these thin walls at the bottom over the arches. By restricting the checker area in the bottom rows, the thickness of the brick may be increased there sufficiently to carry the great weight of the checkers. For instance, we use 3" brick to support 2 $\frac{1}{2}$ " and 2" checker walls.

Many deviations in the detailed construction and application of this restricted checker area may be devised without deviating from the spirit or scope of our invention.

We claim:

1. The method of heating the blast in hot blast stoves, which consists in introducing the blast into the lower portion of a heating chamber, retarding the upward passage of said blast at the lower ends of the heated flues within said chamber, whereby said blast will be evenly distributed to said flues, and expanding said blast and causing it to pass upwardly through said flues at substantially uniform pressure and velocity, after the said retardation.

2. In a hot blast stove, a combination of checker-work composed of bricks laid in courses, arches supporting said checker-work, a course immediately above the supporting arches being composed of bricks of larger size than the bricks employed in the body of the checker-work, whereby the transverse area of the flues is reduced only at the entrance to the flues and the gases are caused to be evenly distributed throughout the body of the checkers.

3. In a hot blast stove, a combination of checker-work composed substantially entirely of courses of bricks of relatively thin section and small size, arches supporting the checker-work, and a relatively very small number of courses of bricks of larger size, each of which course is made up of a num-

ber of bricks substantially equal to the number employed in forming the courses in the main body of the checkers, said courses composed of large bricks being interposed between said main body of checker-work and said arches, thereby reducing the area of the flues at that point, said large size bricks having the double function of transmitting the weight of the checkers to the

arches, and distributing the gases through- 10 out the checker-work.

Signed at South Chicago, Illinois, this 8th day of November, 1915.
